UNITED STATES PATENT OFFICE.

ZACHARY TAYLOR JONES, OF NEW YORK, N. Y.

DESIGN FOR A CHANNEL-IRON.

SPECIFICATION forming part of Design No. 25,414, dated April 21, 1896.

Application filed March 18, 1896. Serial No. 583,823. Term of patent 14 years.

To all whom it may concern:

Be it known that I, ZACHARY TAYLOR JONES, a citizen of the United States, residing in the city of New York, county and State of New York, have invented and produced a new and original Design for a Channel-Iron, of which the following is a specification, reference being had to the accompanying drawing, which forms a part hereof.

10 The drawing represents in perspective a short length of channel-iron which embodies my design.

As represented in the drawing, the lateral members or webs a have each a convexity 15 a' parallel with the middle member b and an

inwardly-inclining plane surface a^2 , being each reverted inwardly upon itself, as at a^3 .

The leading feature of the design is the convexity in each lateral member or web.

What I claim as my invention, and desire 20 to secure by Letters Patent, is—

The design for a channel-iron, substantially as shown and described.

This specification signed and witnessed this 11th day of February, A. D. 1896.

ZACHARY TAYLOR JONES.

In presence of—

HERMAN STEIGER,

HENRY RAINES.
